CLAIM

The ornamental design for a cooking pot top and lid organizer, as shown and described.

DESCRIPTION

FIG. 1 is a perspective view of a cooking pot top and lid organizer, showing my new design;

FIG. 2 is a left end elevational view thereof;

FIG. 3 is a right end elevational view thereof;

FIG. 4 is a top plan view thereof;

FIG. 5 is a side elevational view, the opposite side being a mirror image thereof.

FIG. 4.

FIG. 5.
